Primary Examiner—Mitchell Siegel*Attorney, Agent, or Firm*—Myers, Dawes & Andras LLP[57] **CLAIM**

I claim the ornamental design for the golf ball pouch cleaner, as shown and described.

DESCRIPTION

FIG. 1 is a perspective view of the golf ball pouch cleaner of the present invention;

FIG. 2 is a front elevational view thereof;

FIG. 3 is a left-side elevational view, the right-side being a mirror image thereof; and,

FIG. 4 is a rear perspective view thereof.
